SHAKING CONVEYER

Heinrich Grube, Bochum, Germany, assignor to
 Gebr. Eickhoff Maschinenfabrik und Eisen-
 gesserei, Bochum, Germany

Application June 16, 1936, Serial No. 85,598
 In Germany November 28, 1934

8 Claims. (Cl. 198—220)

The present invention relates to reciprocating shaker conveyers and more particularly to that kind of conveyer the sections of which are joined together by means of flat attachments projecting beyond the side of the trough. Hitherto these attachments have been arranged transversely beneath the trough in form of flat irons with their ends projecting beyond the base of the trough and have carried the trough connecting means. Unless these elements are made very strong their projecting ends readily fracture under the considerable alternating stresses to which they are subdued, and if flat irons of a corresponding strength are employed for example in the form of gusset plates, then in comparison with the trough they are the stronger component, with the result that the localization of stress at the sudden changes in cross section endangers the sheet metal of the trough and the troughs readily tear at the margins of the transverse members at the points where the material is subdued to the largest stress. This effect cannot be improved materially by welding the transverse members to the trough instead of riveting them, because in such a case also the sheet metal of the trough has to take up the main stress at the inward edge of the transverse member and would be subjected to excessive strain at that point even with a welded connection.

According to the invention the mechanical properties of the connecting members are better adapted to those of the material of the trough by abandoning the use of transverse members extending beneath the trough for transmitting the force and by welding a fin-like attachment to the lateral wall of the trough on each side of the trough. This construction is based on the recognition that such a mode of connecting an attached member to the lateral wall of the trough not only successfully withstands the forces arising in the conveyer but is also more favourable for transmitting the forces from the connecting members to the trough than the transverse members extending beneath the base of the trough where the forces are to be transmitted solely by these means. In particular, by suitable configuration of the attachment and by appropriately dimensioning the surfaces of contact with the the walls of the trough, it is possible to allow the forces to be taken up by the walls of the trough without excessive local stresses. For this purpose the attachments are given a cross sectional form which from the point at which the connecting means are applied decreases in dimensions towards the ends of the

attachments in the longitudinal direction of the trough, so that at their ends the attachments are more flexible and thus the occurrence of peak stresses is avoided, whereas hitherto the points at which the rigid transverse members were attached to the trough were points which had to sustain excessive strain and transmit such strain to the trough.

The construction of the transverse members in the form of lateral projections welded to the walls of the trough affords a further advantage. The possibility is afforded of disposing the attachments at least approximately at the level of the centre of gravity of the profile of the trough which gives the advantage that the metal walls of the trough are not subjected to a bending stress over their length. If the connecting members have the form of transverse struts extending obliquely downwardly beneath the trough as has hitherto been customary then it is certainly possible for the ends which carry the connecting means to be bent up to the level of the centre of gravity of the profile of the trough. However, in this case the transverse members are subjected to a very unfavourable strain as they comprise not only elements lying in the plane in which the force is applied but also elements which lie outside this plane and consequently have to withstand torsional forces. Also in this case, the conveyer trough is subjected to bending stresses by the tractional and thrust forces acting on the trough. If, however, the connecting members are arranged in, or approximately in, the plane passing through the centre of gravity of the profile of the trough, then there is no torsional stress on the connecting members and there is no bending stress on the trough. If desired the attachments may be supported by means of a lower extension bearing against the bottom of the trough and in addition the contact surface of the attachments can be such as to reinforce the lateral wall of the trough, the reinforcing member preferably being directed towards the end or ends of the weld at the edge of the base. Finally the attachments may constitute a part of the actual wall of the trough.

In the accompanying drawings Fig. 1 shows in cross section one embodiment of a conveyer trough in accordance with the invention.

Figs. 2 to 4 show a second embodiment in side view, plan view and fragmentary cross section.

Fig. 5 shows a third and Fig. 6 a fourth embodiment.

Fig. 7 shows a fifth and Fig. 8 a sixth embodiment,

Fig. 9 shows a seventh and Fig. 10 an eighth embodiment.

Figs. 11 and 12 show a ninth embodiment in side view and in cross section.

6 At both ends of the trough sections *a*, which may have any desired customary cross section form, attachments *b* are welded to and projected laterally from the side wall of the trough. As seen from Figs. 2 and 3, the attachments have 10 an elongated contact and welding surface *c* of such length that the metal of the trough can take up without excessive stress the forces transmitted from the attachments to the metal trough. In order that the metal trough should 15 not be subjected to the excessive stress at the inward end *e* or at both ends of the attachment *b*, the attachments taper from the part *f* which carries the connecting means towards both ends either in width only as shown in Fig. 3, or in 20 height as shown in Fig. 4, or in both directions as shown in Fig. 2, so that at their ends the attachments merge smoothly into the profile of the trough and no localized stresses arise at the common surfaces. Moreover, as shown in the 25 drawings, the attachments *b* are so shaped that a welded seam *c* is obtained at or near the lower edge of the trough.

The projecting portion *f* of the attachments *b* will be shaped in accordance with the nature of 30 the connecting means employed. For example, as shown in Figs. 1 to 4, the attachments *b* may have flat projecting strips for co-operation with yokes or similar connecting means; in Figs. 5 and 6 the attachments *b* have a loop-like form to 35 receive connecting screws, in which case the attachment may be a rolled member as shown in Fig. 5 or it may be a tubular element with strips welded thereto as shown in Fig. 6. Also, where the attachments have the shape of flat strips 40 they may be in part hollow as indicated in Figs. 7 and 8 instead of being solid as in Fig. 4. In the embodiment shown in Fig. 8, the plate *b* serves substantially for supporting the plate *b* and in this case the plate *b* is subjected to 45 stresses only in its own plane by the forces which it transmits. Moreover, as indicated in Fig. 9, the attachments *b* may extend beneath and bear against the bottom of the trough so as to obtain additional support. As also shown in Fig. 9, 50 the side walls of the trough may be interrupted at *d* where further welded seams are provided. If desired, more than one interruption can be provided.

55 As shown in the modification, according to Fig. 10, the attachments *b* may also constitute a part of the actual walls of the trough.

In addition, as shown in Figs. 1, 2, 4 and 6 and in Figs. 7 to 10, the attachments may be 60 arranged so that at least the part carrying the connecting means is disposed at the level of the centre of gravity *s* of the profile of the trough, so that the metal plates constituting the trough

are not subjected to a bending stress over their entire length.

As shown in Figs. 11 and 12, the attachments 5 may include a fork *g* carrying clamping means *i* and an inverted U-shaped loop *h* opening 10 downwardly into which the clamping means *i* associated with the adjoining trough section can be pivoted. As shown in Fig. 11, the two attachments *g* and *h* may be provided with cylindrical 15 contact surfaces *k*. As indicated on the right hand side of Fig. 12 the shaft *j* on which the clamping means *i* pivots may also serve as the shaft carrying the running wheel of the trough.

In all these cases the attachments may be tapered towards one or both ends in the manner 15 indicated in Figs. 2 and 3.

I claim:

1. In combination with a shaking conveyer trough, connecting means including an element comprising two parts projecting transversely 20 from a lateral wall of said trough, one of said parts adapted to be connected to an adjacent trough, said second part secured at one end to said first part and welded at the other end to at least one of the walls of said first trough, said 25 second end gradually decreasing in width in longitudinal direction of said walls at least at one side of said first part so as to merge gradually into said wall.

2. In combination with a shaking conveyer 30 trough, connecting means including an element comprising two parts projecting transversely from a lateral wall of said trough, one of said parts adapted to be connected to an adjacent trough, said second part secured at one end to 35 said first part and welded at the other end to at least one of the walls of said first trough, said second part gradually decreasing in thickness from said first end toward said second end at least at one side of said first element, said second 40 end gradually decreasing in width in longitudinal direction of said wall at least at one side of said first element so as to merge gradually into said wall.

3. A shaking conveyer according to claim 1, 45 said second part being welded to said first trough adjacent the lower edge of said lateral wall.

4. A shaking conveyer according to claim 1, 50 said second part constituting a reinforcement of said walls.

5. A shaking conveyer according to claim 1, 55 at least one of said walls having an opening therein, said second part being welded to said wall to close said opening.

6. A shaking conveyer according to claim 1, 60 said first part comprising a flat element adapted to be embraced by a pivotal yoke.

7. A shaking conveyer according to claim 1, 65 said second part forming a portion of said wall.

8. A shaking conveyer according to claim 1, 70 said first part including an eye adapted to receive a connecting screw.

HEINRICH GRUBE.
